(57) **CLAIM**

The ornamental design for an electronic device charger, as shown and described.

DESCRIPTION

FIG. 1 is a front elevational view of an electronic device charger showing my new design;

FIG. 2 is a rear elevational view thereof;

FIG. 3 is a left side thereof, the right side being a mirror image thereof;

FIG. 4 is a top plan view thereof;

FIG. 5 is a bottom plan view thereof;

FIG. 6 is a perspective view thereof;

FIG. 7 is a front elevational view of a second embodiment of an electronic device charger showing my new design;

FIG. 8 is a rear elevational view thereof;

FIG. 9 is a left side thereof, the right side being a mirror image thereof;

FIG. 10 is a top plan view thereof;

FIG. 11 is a bottom plan view thereof; and,

FIG. 12 is a perspective view thereof.

The broken lines in the figures represent portions of the article which form no part of the claim.

1 Claim, 6 Drawing Sheets
